UNITED STATES PATENT OFFICE.

HERMAN E. GOTHLBERG, OF ROSELLE PARK, NEW JERSEY.

METALLIC-TREAD MAT.

Application filed February 12, 1919. Serial No. 276,643.

To all whom it may concern:

Be it known that I, HERMAN E. GOTHLBERG, a citizen of the United States, and a resident of Roselle Park, county of Union, 5 State of New Jersey, have invented certain new and useful Improvements in Metallic-Tread Mats, of which the following is a specification.

This invention relates to metallic tread mats and has for its primary object to provide a simple and inexpensive means in a mat structure of this character which will effectually prevent slipping or sliding of the mat upon the floor surface, which results 10 in marring of the surface and the possibility of injury to the person treading upon the mat.

The invention more particularly contemplates an improvement in that type of metallic thread mat which is made up of a multiplicity of flexibly connected metallic units, said improvement consisting primarily in friction members interposed between the units in adjacent rows and projecting above and below the opposite side faces of the mat so that said members will not only support the metal parts out of contact with the floor surface but will also afford a cushioning means which prevents direct contact of the shoes with the metal units of the mat. There is thus afforded a somewhat yielding tread surface so that the shock or jar which would otherwise be transmitted to the body of the person treading 25 on the mat is minimized and excessive wear upon the shoes is also practically eliminated.

It is further a general object of my invention to provide a metallic tread mat having the above noted desirable features in the construction of which materials which would otherwise be wasted may be utilized so that the mat as a whole may be manufactured at a cost not appreciably greater 40 than is incurred in the production of the ordinary metallic mat of this character now known in the art.

With these and other objects in view, an embodiment of my invention is shown in 45 the accompanying drawing; and this embodiment will be hereinafter more fully described with reference thereto, and the invention will be finally pointed out in the claims.

50 In the accompanying drawing:

Figure 1 is a plan view of a metallic tread

mat illustrating one practical embodiment of my invention;

Figure 2 is a sectional view thereof taken on the line 2—2 of Figure 1; and 60

Figure 3 is a detail elevation of one of the friction members.

Referring in detail to the drawing wherein like reference characters designate corresponding parts throughout the several 65 views, 5 designates the metallic units which together constitute the body of the mat structure. Each of these units as shown in Figure 1, consists of a sheet metal strip bent, preferably, into rectangular form and having the parallel longitudinal side portions 6 and the transverse portions 7 which are outwardly bent, or bowed as shown. The extremities of the metal strip are arranged in lapping engagement, and these extremities as well as the side portions 6 of the 70 tread units are formed with openings to receive the metal wire rods 8 which flexibly connect the several units of the mat structure to each other. As herein shown, the 75 metal units 5 are arranged in parallel rows, the units in one row alternating with respect to the units in the adjacent rows and being disposed with respect to each other so that their several rod receiving openings are in 80 registration to receive a tie-rod extending across the entire width of the mat. Each of these rods is bent to provide parallel portions which connect one unit in one row to two of the units in the adjacent rows. The 85 terminals of the rod are inwardly bent and fitted within the ends of a connecting sleeve (not shown). It will be understood that 90 the specific form of the metallic units and the method of their connection which I have 95 just described, constitutes no essential part of the present invention which may be adapted and applied to metallic mat structures of this general character by resort to such obvious modifications as may appear necessary.

The present improvement consists in the provision of the friction members 10 which preferably, though not necessary, consist of a composition of rubber and canvas or other 105 fabric. Each of these members is substantially of a length equal to the length of the mat units and they are preferably cut out of a sheet of material in the shape or form shown in Figure 3 of the drawing, said 110 members having a waving or undulating edge surface as shown at 11. These mem-

bers 10 are arranged as illustrated in Figure 1, between the metal units 5 in each row and the two contiguous units in an adjacent row and have openings 12 formed in their end portions for the reception of the tie-rods 8. Each unit bears against one side portion 6 of the metal units 5 in one row and in order to reinforce the flexible friction member and prevent the same from buckling 10 between the adjacent tie-rods 8, a metal plate 13 is associated with each unit and at its ends is disposed between the contiguous units of the adjacent row and the friction member, said plate likewise having openings 15 which register with the openings in the friction member and receive the tie-rods.

The friction members 10 are preferably of such width that their undulating longitudinal edges project beyond the corresponding edges of the mat units 5 and of the plates 13. These members may be of any desired thickness, though I have found in practice that a thickness of about one eighth of an inch is sufficient in order to afford a firm frictional contact upon the floor surface and the desired cushioning function in the mat structure. These members 10 may be cut or stamped out from old tire casings or formed from other materials 25 which would otherwise be a source of waste and monetary loss. This feature is one of no small importance, as it enables the tread mat to be produced at a cost which will not be greatly in excess of the ordinary mat of 30 this type now upon the market.

From the foregoing description taken in connection with the accompanying drawing, the construction as well as the several advantages in practical use of my improved 40 tread mat, will be clearly and fully understood. When the mat is arranged upon the floor surface, the friction members 10 engaging such surface will effectually prevent the slipping or sliding of the mat when pressure is applied thereon by the foot at an angle to the perpendicular. This is particularly true when the mat is used on marble floors. It is also seen that as the friction members support the metallic units of the 45 mat structure out of contact with the floor surface, the latter will not be scratched or otherwise marred. Further, it is to be noted that these friction members project above the upper edges of the metal units so that the 50 sole of the shoe does not come into direct contact with the latter. Thus, the shoe will not be unduly worn and the friction members which are composed of rubber and fabric afford a resilient cushion so that even 55 when the foot is placed upon the mat with considerable force, shock or jar which would otherwise be transmitted to the body is to a large extent eliminated. A further advantage incident to the provision of the 60 members 10 with the undulatory edges is

that each member has a plurality of points of frictional contact with the floor surface and will thus more effectively prevent slipping of the mat. These floor engaging edges of the members 10 will wear uniformly so 70 that the area of frictional contact with the floor surface will remain practically the same until the projecting portions of said members have been completely worn away.

In the preceding description and the accompanying drawings I have disclosed one practical embodiment of the invention, which, however, may likewise be exemplified in numerous alternative constructions. Accordingly the invention as herein claimed 75 is to be considered as inclusive of all legitimate equivalents for the various elements employed as well as other contemplated arrangements thereof, which may satisfactorily accomplish the desired results.

I claim:

1. A mat comprising a series of rows of substantially rectangular links disposed in staggered relation with unfilled spaces within the links, flexible rods passing through the end portions of the links to secure same together, and elongated narrow tread and supporting blocks situated outside the spaces confined within the links and each placed against one side of a link with its opposite 90 end portions disposed beside the two end portions of adjoining staggered links, said blocks having corrugated upper and lower surfaces and being secured in the mat structure by the passage therethrough of said 95 flexible rods, and plates also secured by the rods and extending against the free sides of the blocks opposite the spaces between the adjoining staggered links.

2. A mat comprising a series of rows of links being substantially rectangular and disposed in staggered relation with open unfilled spaces within the links, flexible rods passing through the end portions of the links to secure same together, and elongated 100 narrow tread and supporting blocks situated outside the spaces confined within the links and each placed against one side of a link with its opposite end portions disposed beside the two end portions of adjoining staggered links, said blocks being made of reinforced resilient material having corrugated 105 upper and lower edge portions projecting above and below the normal plane of the mat structure, said blocks being secured in 110 the mat by the passage therethrough of said flexible rods, and backing plates placed against the free sides of the links opposite the spaces between the adjoining staggered 115 links and secured by the flexible rods.

In testimony that he claims the foregoing as his invention, he has signed his name hereunder.

HERMAN E. GOTHBERG.
